SNATCH BLOCK

George J. Armstrong, Seminole, Okla.

Application January 18, 1939, Serial No. 251,601

2 Claims. (Cl. 254—194)

This invention relates to pulley blocks, and more particularly to what is commonly known in the art as "snatch blocks" generally used extensively in oil fields, logging camps, mines, and ships, and in connection with suitable machinery or automotive trucks, and in association with a rope or cable for pulling or moving heavy loads. For such type of work it is necessary to attach a hook to the end of the rope or cable, and due to the fact that the hook used and attached to the rope or cable is often too large to pass through the snatch block, it is necessary that the snatch block be so constructed as to be quickly and easily opened for inserting the rope or cable therein, and which also may be closed securely after the rope or cable has been so inserted.

An object of the present invention is therefore to provide a snatch block which will meet all the requirements aforementioned; and the invention together with its objects and advantages will be best understood from a study of the following description taken in connection with the accompanying drawings wherein:

Figure 1 is a side elevational view of the snatch block in completely assembled condition.

Figure 2 is a longitudinal sectional view through the snatch block in completely assembled condition.

Figure 3 is a top plan view of one section of the snatch block.

Figure 4 is an edge view of the section of the snatch block shown in Figure 3.

Figure 5 is a view looking toward the inner side or face of the section of the block shown in Figures 3 and 4.

Figure 6 is an edge view of the other snatch block section.

Figure 7 is a view of the inner face of said other section.

40 Referring more in detail to the drawings it will be seen that in the preferred embodiment thereof the snatch block comprises, essentially, a block indicated generally by the reference numeral 5, a hook 6, and a pulley 7.

45 The block 5 is composed of two complementary sections 8 and 9, each section being in the form of a plate and provided at the head or upper end thereof with a lateral projection, the projection of the section 8 being indicated by the reference numeral 10 and the projection of the section 9 being indicated by the reference numeral 11.

50

The head part 10 of the section 8 is provided with a through opening 12 for accommodating the shank 13 of the hook 6. At the inner end

thereof the opening 12 is counter-bored as at 14, and as best shown in Figure 2 to accommodate the head 15 on the free end of the shank 13.

Head 10 also has extending radially from the opening 12 to one face or side of the head 10 a slot 16 through which the shank 13 is passed into the opening 12.

Also the section 8 of the block is provided with an integral spindle or axle 17 for the pulley 7. The block section 8 is provided with

The block section 9 is provided with an opening 18 to accommodate the free end of the axle 17 as also best shown in Figures 2, 6 and 7.

Head 10 of section 8 has its upper and lower surfaces curved or disposed on an arc as shown and on the top side thereof is formed to provide a groove 19 and a tongue 20, groove 19 and tongue 20 being intersected by the slot 16 as clear from a study of Figure 3.

The head 11 of section 9 also has its top and bottom surfaces curved or disposed on an arc, and at the underside thereof the head 11 of section 9 is formed to provide an arcuate tongue 21 to match the groove 19 and an arcuate groove 22 to match the tongue 20 of the head 10 associated with section 8 of the block.

It will thus be seen that after the shank 13 of hook 6 has been properly engaged with the head section 10 of section 8 and pulley 7 placed on the spindle or axle 17 the free end of the axle 17 is positioned within the opening 18 in section 9 after which section 9 is rotated about the axle 17 as an axis and relative to section 8 of the block to engage the tongue 21 of section 9 with groove 19 of block section 8, and the groove 22 of section 9 with the tongue 20 of section 8. Thus the sections 8 and 9 are placed opposite one another and in assembled position with the head 11 of section 9 closing the slot 16 to thereby retain the shank 13 of hook 6 within the opening 12, and the pulley 7 confined on the axle 17 between the sections 8 and 9.

Section 9 on the outer side thereof is also provided with a recess 23 in which is accommodated a latch member 24 pivoted within the recess 23 as at 25.

The latch member 24 is provided adjacent one end thereof with a lug or extension 26 that projects into the slot 16 through a hole 16' in the bottom of the slot 16 and thus this latch member serves to retain the sections 8 and 9 against relative movement relative to one another.

With the sections 8 and 9 of the block assembled the projection 26 of the latch 24 is normally urged into position within the slot 16 through the medium of a coil spring 27 accom-

modated within the recess 23 and bearing against an end of the latch member 24 as clearly shown in Figure 2.

It will thus be seen that in use, when it is desired to engage a cable or rope with the pulley 7 pressure is applied to the latch 24 to move the latch to a released position whereupon block section 9 may then be rotated relative to section 8 to separate the section 9 from the section 8. With the section 9 so displaced a cable may, in an obvious manner, be engaged with the pulley 7 after which the section 9 of the block is rotated to re-engage tongue 21 with groove 19, and tongue 20 with groove 22, the sections of the block being then secured in assembled position through the medium of the latch 24 and in a manner hereinbefore described.

It is thought that a clear understanding of the construction, manner of assembling the snatch block, and the utility and advantages of such a snatch block structure and assembly will be had without a more detailed description.

Having thus described the invention what is claimed as new is:

1. A snatch block assembly comprising a block proper composed of a pair of complementary sections each including a plate-like body and an integral head, the head of each section being arcuate and provided with an arcuate tongue and an arcuate groove, an axle extending laterally from one section and the other section having a hole therein for receiving the axle, said sections being rotatable relative to one another on said axle to effect engagement or disengagement of the tongue and groove of one section with the tongue and groove of the complementary section, the head of one of said sections being provided with a through opening and a slot extending from one side of said head inwardly to merge with said opening, a hook having a shank insert-

able into said opening through said slot, said shank being provided on the free end thereof with a retaining head, and the head of the second-named block section serving to close said slot for retaining the shank of said hook within said opening, a pulley supported by the axle and latch means carried by one section and engaging a part of the other section to prevent relative movement of the sections.

2. A snatch block assembly comprising a block proper composed of a pair of complementary sections each including a plate-like body and an integral head, the head of each section being arcuate and provided with an arcuate tongue and an arcuate groove, one of said sections also being provided with a lateral pulley-accommodating axle, and the other of said sections being provided with an aperture to accommodate the free end of said axle, said sections being rotatable relative to one another to effect engagement or disengagement of the tongue and groove of one section with the tongue and groove of the complementary section, the head of one of said sections being provided with a through opening and a slot extending from one side of said head inwardly to merge with said opening, and a hook having a shank insertable into said opening through said slot, said shank being provided on the free end thereof with a retaining head, and the head of the second-named block section serving to close said slot for retaining the shank of said hook within said opening, and a spring-biased latch member pivotally mounted on the second-named section and provided with a projection accommodated within said slot and co-operable with the side walls of the slot for securing the block sections against relative rotative movement.

GEORGE J. ARMSTRONG.
